FOOD SERVICE CART

Richard J. McCooey, 1226 36th St. NW.,
Washington, D.C. 20007

Filed June 26, 1973, Ser. No. 373,632

Term of patent 14 years

Int. Cl. D12—02

U.S. Cl. D12—22

FIG. 1

FIG. 2

FIG. 3

FIG. 4

FIG. 5

FIG. 1 is a front perspective view of a food service cart showing my new design;

FIG. 2 is a left-side elevational view thereof;

FIG. 3 is a rear elevational view thereof;

FIG. 4 is a right-side elevational view thereof; and

FIG. 5 is a top plan view thereof.

I claim:

The ornamental design for a food service cart, substantially as shown.
